CABINET

Elizabeth D. Hartzell, 417 W. Barry, Chicago, Ill.

Filed Sept. 18, 1961, Ser. No. 66,730

Term of patent 14 years

(Cl. D33—19)

FIG. 1

FIG. 2

FIG. 3

FIG. 2 is a side view of the same.

FIG. 3 is a front view of the same showing the table portion in position for use, and

FIG. 4 is a side view of the article as shown in FIG. 3.

The sides opposite to those of FIGS. 2 and 4 are similar in appearance while the back and the top are plain and unornamented. The essential features of the design are shown in solid lines on the drawings.

I claim:

The ornamental design for a cabinet, as shown and described.
